CALIFORNIA.

ELECTRIC AUTOMATIC TRAIN STOP, TELEPHONE, AND BLOCK-SIGNAL SYSTEM.

1,149,159.

Specification of Letters Patent.

Patented Aug. 3, 1915.

Application filed January 26, 1914. Serial No. 814,373.

To all whom it may concern:

Be it known that we, WILLIAM J. CRABBE, a subject of the King of England, residing at Drum, in the county of Placer and State 5 of California, and HARRY B. RODEHAVER, a citizen of the United States, residing at East Auburn, in the county of Placer and State of California, have invented new and useful Improvements in Electric Automatic Train 10 Stop, Telephone, and Block-Signal Systems, of which the following is a specification.

This invention relates to an electric, automatic train stop, telephone and block signal system.

15 The object of this invention is to provide a simple, reliable, easily operated electric, automatic train stop, telephone and block signal system which can be easily installed and operated in connection with the standard forms of existing tracks and lines.

Other objects will hereinafter appear.

The invention consists of the parts and the construction and combination of parts as hereinafter more fully described and 25 claimed, having reference to the accompanying drawings, in which—

Figure 1 is a diagrammatic view of the whole connected system. Fig. 2 is a diagrammatic view of the telephone circuit.

30 Referring to the drawings, A indicates a continuous rail bonded so that it will conduct an electric current. This will hereinafter be known as the "common rail."

B is an ordinary rail, which is shown as 35 divided into three blocks generally indicated at 2, 3 and 4. These blocks can be of any desired length but are insulated electrically from each other. When a train comes into a block, as indicated at 3, it completes the 40 following circuit: Starting from battery 5 the current passes through the wire 6, common rail A, the wheels and axle of the locomotive indicated at 7, rail B, wire 8 and magnet 9 to a wire 10 and back to the battery, completing a circuit through magnet 9.

Pivotedly mounted, as at 11, with relation to the magnet 9, is a switch bar 12 operated by magnet 9. This switch bar normally assumes the position indicated at 12^a, Fig. 1, 50 on the opposite side from switch bar 12, but is lifted into the closed position, indicated at 12, when magnet 9 becomes energized which occurs when a train enters the connected block. The closing of the switch bar

12 closes a local circuit through contacts 55 13 and 14, battery 15, and a light 16, and suitable means, indicated by the dotted lines 17, are provided and are operable in connection with magnet 9 for the purpose of throwing the semaphore arm 18 into danger 60 position.

Referring to Fig. 1, it will be seen that four electromagnets 9, 9^a, 9^b and 9^c are provided, two for each block. The entrance of a train into block 3 simultaneously closes a 65 circuit similar to the one just described through electromagnet 9^b and also establishes a local circuit through a light 16^b and battery 15^b by operating the switch bar 12^b similar to the operation of the bar 12. The 70 semaphore arm 18^b is also operated in unison with the electromagnet 9^b, and light 16^b is similarly illuminated by the closing of the circuit through battery 15^b. The entrance of a train into a block will thus cause 75 the display of the semaphore arms 18 and 18^b into danger position and will also display an auxiliary signal, such as lights 16 and 16^b. A warning is thus given to an on-coming train whether it be approaching from the 80 front or the rear of the block in which train 7 is traveling.

Means have also been provided for automatically setting the brakes on the locomotive when two trains happen to approach 85 each other on the same track. This is accomplished in the following manner and the circuit here described will be known as the "brake circuit": Suitably positioned between the common rail A and the second rail 90 B is a third rail C, or other connection, such as an overhead trolley, but preferably the third rail here shown laid in the center of the tracks. This third rail is insulated for a very low voltage and bonded for heavy 95 current and is divided into blocks similar to rail B, as indicated at B' and B''. Each locomotive is provided with a contact shoe 19, of suitable construction, which is adapted to make a continuous contact with the third 100 rail C, an electromagnet 20 suitably connected through an armature lever 21 with the steam or air operated brake valve 22, a telephone 23, and a double-throw, double-pole switch 24. The operation will be as 105 follows: Supposing that a train, indicated at 7^a, happens to approach train 7 from block 4, a circuit will immediately be estab-

lished to operate the electromagnets and automatically set the brakes. This circuit can be traced as follows: 25 indicates a battery and 26 indicates a triple-pole, double-throw switch, the position of which is controlled by the station operator. Its normal position is that indicated in Fig. 1 where it is in circuit with the battery 25. The current will travel as follows: Commencing with battery 10 25 the current passes out through wire 27, contact 28, switch bar 12^b, contact 29, wire 30, third rail C, contact shoe 19 and wire 31; then through one of the arms of the double-pole, double-throw switch 24, magnet 20, 15 back through the opposite arm of the switch 24, wire 32, axle and wheels 7, common rail A, axle and wheels 7^a of the opposite train, wire 32^a, double-pole, double-throw switch 24^a, electromagnet 20^a, back through the opposite arm of the switch 24^a, wire 31^a, contact shoe 19^a, third rail C, wire 30^a, contact 29^a, switch bar 12^c, contact 28^a, wire 27^a, outside arm of switch 26 and back to the battery 25. A circuit is thus established 20 through the electromagnets 20 and 20^a on the opposite locomotives, and the connected armature levers 21 will thus be operated to open the respective air brake valves 22 and automatically set the brakes. The engineers 25 on the respective locomotives when the trains are thus stopped will now naturally want orders from the nearest operator and a telephone circuit has therefore been provided for this purpose. Each locomotive, 30 as before described, is provided with a telephone 23 and a double-pole, double-throw switch 24 by which the telephone may be thrown into a circuit, hereinafter to be described. The double-pole, double-throw 35 switch 24 is, however, not thrown into circuit with the telephone until the brakes upon the respective locomotives have been released by opening the circuit through the respective magnets 20 and 20^a. This is performed by the operator and is accomplished 40 by throwing the triple-pole, double-throw switch 29 from the position indicated in Fig. 1 into the opposite position indicated in Fig. 2 or in circuit with contacts 33 on the telephone circuit. The operator at the 45 station is automatically informed or in other words given an alarm to indicate that the trains have met and that they have been automatically stopped. This alarm is given 50 by a gong, indicated at 34, and the circuit through said gong is closed simultaneously with the closing of the circuit through the brake magnets 20 and 20^a which is accomplished by operating the respective switch 55 bars 12^c and 12^b. The circuit through the gong 34 passes from a local battery 35, with connected wire and the contacts indicated at 60 36. It can thus be seen that the setting of the brakes when two trains approach is automatically brought to the notice of the station

operator by the operation of the alarm gong 34 or any other suitable means operated by the local circuit through battery 35. This immediately indicates to the station operator what has happened and in order to 70 place himself in communication with the engineers of the respective locomotives the first operation necessary is to throw the triple-pole switch 26 over into engagement with the opposite contacts 33 to establish a 75 telephone circuit and also to break the circuit through the brake magnets 20 and 20^a upon the respective locomotives. The moment switch 26 is thrown into this position by the station operator it can easily be seen that the brake magnets 20 and 20^a immediately become deenergized and that the connected brake air levers are consequently released. This immediately indicates to the 80 respective engineers that the operator is on 85 the telephone circuit and desires to communicate with them. Each engineer then throws his respective double-pole, double-throw switch 24 into engagement with the contacts 37 on the locomotive telephone circuit, and this circuit can be traced by referring to Fig. 2 which is a diagram of the telephone circuit only. Each circuit is similar to the locomotive brake circuit with the one exception that in place of passing the 90 current through the brake magnets 20 and 20^a the circuit is switched through the respective telephones and the circuit may be traced as follows: Commencing from telephone 40 the current passes through the 100 middle leg of switch 33 and through wire 41 to the common rail A, from where the current passes through the wheels and axles of locomotives 7 and 7^a, wires 32 and 32^a, and one leg of each switch 24 and 24^a to one side 105 of the telephones 23 and 23^a. The other side of the parallel circuit passes from the other terminal of telephone 40, through the two outside legs of switch 33, through wires 27 and 22^a, contacts 28 and 28^a, wires 30 and 30^a to adjacent sections of the third rail C, 110 from where the current passes through shoes 19 and 19^a, with connected wires, to the opposite terminal of the previously mentioned locomotive telephones. The provision of 115 the auxiliary connection 41 completes the parallel circuit which not only permits the engineers to communicate with each other, but also permits the operators of the telephones 40 and 42 to communicate with each other, or with both or either engineer. Connection can at the same time be made through the telephone 40 or 42 with the usual outside telephone circuit. From the foregoing description it can be seen that 120 each engineer will receive his respective orders and can then proceed in the direction dictated by the operator. Each engineer then throws his respective double-pole, double-throw switch 24 and 24^a back into circuit 125 130

cuit with the brake magnets 20 and 20^a so that the automatic braking mechanism will be in readiness for automatic operation with relation to the remainder of the circuit on

5 the system, or any automatic mechanism may be provided for the purpose of returning the switch to the brake circuit.

The automatic stop, block signal and telephone system constructed and connected as 10 here shown may be cheaply installed and can be operated on a low voltage current, and the circuits established may be controlled from a local set of batteries and can thus be easily taken care of and tested from 15 time to time to guard against leakages and waste of current.

The telephone circuit may be connected with the usual telephone carried on poles along the sides of the track, while the 20 remaining connecting circuits are simply connected with the tracks which then act as conductors for the several circuits. Perfect insulation at any point is not absolutely necessary as a low voltage current is all that 25 is necessary for the purpose of operating the different magnets and connected switches.

The connection between the magnets 9 and the semaphore arms 18 may be accomplished in any suitable manner (not here shown), as 30 it is not necessary for the successful operation of the system to provide any particular connection at this point. Similar switch bars 12, with connected double-pole and double-throw switches, may be suitably constructed to suit conditions and local requirements. The materials and finish of the several parts of the apparatus may likewise be 35 changed and installed according to the judgment and requirements of the manufacturers.

40 Having thus described our invention, what we claim and desire to secure by Letters Patent is—

1. The combination with a common continuous rail conductor, of a second rail divided into blocks, a third rail parallel with the second rail similarly divided into blocks, a battery connected on one side with the common rail, a pair of electromagnets having their lower terminals connected respectively with adjacent sections of the second rail on different sides of the block and having their upper terminals connected with the battery, pivotally mounted switch bars operated by the electromagnets, a pair of 45 contact members connected respectively with adjacent sections of the third rail, a pair of contact members connected with a second battery through a switch, said switch bars controlling the connection between said contact members, a pair of locomotives, one in each block, an electromagnet on each locomotive having their lower terminals connected through contact shoes with the third rail and their upper terminals grounded on the common and second rails, and valves on each 50 locomotive controlled by the electromagnets on the locomotives for actuating the air brakes, means controlled by a station operator for breaking the circuit through the electromagnets on the locomotives, a telephone for the station operator, a telephone on each 55 locomotive, and a double-pole, double-throw switch on each locomotive for throwing the telephones into circuit with the station telephone.

60 65

locomotive controlled by the electromagnets on the locomotives for actuating the air brakes.

2. The combination with a common continuous rail conductor, of a second rail divided into blocks, a third rail parallel with the second rail similarly divided into blocks, a battery connected on one side with the common rail, a pair of electromagnets having their lower terminals connected respectively with adjacent sections of the second rail on different sides of the block and having their upper terminals connected with the battery, pivotally mounted switch bars operated by the electromagnets, a pair of contact members connected respectively with adjacent sections of the third rail, a pair of contact members connected with a second battery through a switch, said switch bars controlling the connection between the contact members, a pair of locomotives, one in each block, an electromagnet on each locomotive having their lower terminals connected through contact shoes with the third rail and their upper terminals grounded on the common and second rails, valves on each locomotive controlled by the electromagnets on the locomotives for actuating the air brakes, and means controlled by a station operator for breaking the circuit through the electromagnets on the locomotives.

3. The combination with a common continuous rail conductor, of a second rail divided into blocks, a third rail parallel with the second rail similarly divided into blocks, a battery connected on one side with the common rail, a pair of electromagnets having their lower terminals connected respectively with adjacent sections of the second rail on different sides of the block and having their upper terminals connected with the battery, pivotally mounted switch bars operated by the electromagnets, a pair of contact members connected respectively with adjacent sections of the third rail, a pair of contact members connected with a second battery through a switch, said switch bars controlling the connection between said contact members, a pair of locomotives, one in each block, an electromagnet on each locomotive having their lower terminals connected through contact shoes with the third rail and their upper terminals grounded on the common and second rails, valves on each locomotive controlled by the electromagnets on the locomotives for actuating the air brakes, means controlled by a station operator for breaking the circuit through the electromagnets on the locomotives, a telephone for the station operator, a telephone on each locomotive, and a double-pole, double-throw switch on each locomotive for throwing the telephones into circuit with the station telephone.

4. The combination with a common con-

tinuous rail conductor, of a second rail divided into blocks, a third rail parallel with the second rail similarly divided into blocks, a battery connected on one side with the 5 common rail, a pair of electromagnets having their lower terminals connected respectively with adjacent sections of the second rail on different sides of the block and having their upper terminals connected with 10 the battery, pivotally mounted switch bars operated by the electromagnets, semaphore arms connected with and operated by said switch bars, a pair of contact members connected respectively with adjacent sections of 15 the third rail, a pair of contact members connected with a second battery through a switch, a pair of locomotives, one in each block, an electromagnet on each locomotive having their lower terminals connected 20 through contact shoes with the third rail and their upper terminals grounded on the common and second rails, and valves on each locomotive controlled by the electromagnets on the locomotives for actuating the air 25 brakes.

5. The combination with a common continuous rail conductor, of a second rail divided into blocks, a third rail parallel with the second rail similarly divided into blocks, 30 a battery connected on one side with the common rail, a pair of electromagnets having their lower terminals connected respectively with the adjacent sections of the second rail on different sides of the block and having their upper terminals connected with the battery, pivotally mounted switch bars operated by the electromagnets, a pair of 35 contact members connected respectively with adjacent sections of the third rail, a pair of contact members connected with a second battery through a switch, a pair of locomotives, one in each block, an electromagnet on each locomotive having their lower terminals connected through contact 40 shoes with the third rail and their upper terminals grounded on the common and second rails, valves on each locomotive controlled by the electromagnets on the locomotives for actuating the air brakes, a telephone for the station operator, a telephone on each locomotive, means for throwing the telephones into circuit with the station telephone and with each other, and a switch 45 controlled by the station operator for breaking the circuit through the electromagnets on the locomotives, said switch being also adapted to open or close the circuit between the locomotive telephones and the operators' telephones.

third rail and their upper terminals grounded on the common and second rails, and valves on each locomotive controlled by the 50 electromagnets on the locomotives for actuating the air brakes.

6. The combination with a common continuous rail conductor, of a second rail divided into blocks, a third rail parallel with 55 the second rail similarly divided into blocks, a battery connected on one side with the common rail, a pair of electromagnets having their lower terminals connected respectively with the adjacent sections of the second rail on different sides of the block and having their upper terminals connected with the battery, pivotally mounted switch bars operated by the electromagnets, a pair of 60 contact members connected respectively with adjacent sections of the third rail, a pair of contact members connected with a second battery through a switch, a pair of locomotives, one in each block, an electromagnet on each locomotive having their 65 lower terminals connected through contact shoes with the third rail and their upper terminals grounded on the common and second rails, valves on each locomotive controlled by the electromagnets on the locomotives for actuating the air brakes, a telephone for the station operator, a telephone on each locomotive, means for throwing the telephones into circuit with the station telephone and with each other, and a switch 70 controlled by the station operator for breaking the circuit through the electromagnets on the locomotives, said switch being also adapted to open or close the circuit between the locomotive telephones and the operators' 75 telephones.

In testimony whereof we have hereunto set our hands in the presence of two subscribing witnesses.
